(57) **CLAIM**

The ornamental design for a transparent nib for digital stylus, as shown and described.

DESCRIPTION

FIG. 1 is a front-right-top perspective view of a transparent nib for digital stylus according to our new design;

FIG. 2 is a rear-left-bottom perspective view thereof;

FIG. 3 is a front elevational view thereof, wherein the rear elevational view is a mirror image of the front elevational view;

FIG. 4 is a top plan view thereof;

FIG. 5 is a bottom plan view thereof;

FIG. 6 is a left side elevational view thereof; and,

FIG. 7 is a right side elevational view thereof.

The dashed broken lines in the drawings show portions of the transparent nib for digital stylus that form no part of the claimed design. The dot-dot-dash broken lines in the drawings indicate environmental subject matter and form no part of the claimed design.
